STOPPING MECHANISM FOR LOOMS

Oscar V. Payne, Worcester, Mass., assignor to Crompton & Knowles Loom Works, Worcester, Mass., a corporation of Massachusetts

Application April 4, 1932, Serial No. 603,166

11 Claims. (Cl. 139—371)

This invention relates to means for stopping a loom before complete exhaustion of weft or filling. While capable of general application, the invention is particularly designed for use in connection with looms having more than one shuttle, such as a 2 x 1 box loom.

It is the general object of the invention to provide mechanism for indicating substantial weft exhaustion in the active shuttle and for stopping the loom a predetermined number of picks after such indication.

The invention is shown and described herein as applied to a 2 x 1 loom in which each shuttle is alternately active for two successive picks, and in which it is desired to stop the loom with the indicated shuttle at the plain or single box end of the loom.

While applicable to a box loom using two or more shuttles, my invention does not depend in any way on the shifting of the shuttle boxes or on any operation of the box mechanism, and may be used in a plain loom to delay loom stoppage for any desired number of picks.

My invention further relates to improved and simplified devices by which the described object may be attained, and to arrangements and combinations of parts which will be hereinafter described and more particularly pointed out in the appended claims.

A preferred form of the invention is shown in the drawings, in which

Fig. 1 is an end elevation of portions of a loom embodying my improvements;

Fig. 2 is a side elevation of the pick-counting and contact mechanism, with the cover plate removed;

Fig. 3 is an end view of the parts shown in Fig. 2 but with the cover plate in position;

Fig. 4 is a view similar to Fig. 2 but showing the parts in re-set or normal position;

Figs. 5 and 6 are detail sectional views, taken along the lines 5—6 and 6—6 in Fig. 4 respectively;

Figs. 7, 8, 9 and 10 are views similar to Figs. 2 and 4 but showing the parts in additional relative positions;

Fig. 11 is an end view, looking in the direction of the arrow 11 in Fig. 7;

Fig. 12 is a plan view, taken substantially along the line 12—12 in Fig. 2;

Fig. 13 is a diagrammatic view showing the electrical connections, and

Fig. 14 is a detail sectional view, taken along the line 14—14 in Fig. 2.

Referring to the drawings, I have shown portions of a loom including a loom frame 20, a lay 21, a shuttle S, a weft detecting mechanism D, a counting and contact mechanism C, a shipper lever 22 pivoted to the loom frame at 23, and a brake lever 24 pivoted to the loom frame at 25,

all of which parts, with the exception of the counting mechanism C, are of a usual commercial construction.

The weft detector is not shown in detail herein but comprises a detecting member 27 mounted in a casing 28 and positioned to extend into a shuttle S and engage the weft or filling on a bobbin therein. The detecting member 27 is preferably of the side-slipping type and is so constructed and supported that the detector 27 will slip sidewise, longitudinally of the bobbin in the shuttle S, upon the occurrence of an insufficient supply of weft on said bobbin.

The counting and contact mechanism C comprises a casing 30 mounted in fixed position on the loom frame 20 and having a removable cover plate 31. An actuating member 33 (Fig. 4) is provided with a slot 34 through which loosely extends a stud 35 (Fig. 6) fixed in the casing 30. The member 33 is yieldingly maintained in the rearward position shown in Figs. 2 and 4 by a spring 37, connected at one end to a pin 38 in the upper edge of the member 33 and connected at the other end to a pin 39 fixed in the casing 30.

The outer end of the member 33 projects through a slot 40 in the rear edge of the casing 30 and normally rests upon the upper end of a support 42, pivoted on a stud 43 threaded into the bottom of the casing 30. A coil spring 44 (Fig. 14) is seated at one end in a pocket in the side of the support 42 and at the other end in a depending portion 45 (Fig. 5) of the casing 30 and yieldingly holds the support in operative position.

The member 33 is provided with notches 46 on its lower face and also has a portion 47 extending beyond the pivot 35 and underlying a shoulder 48 on a re-setting stud 49.

A holding bar 50 is also pivoted on the stud 35, but without endwise lost motion thereon, and is spaced from the member 33 by a washer 52 (Fig. 6). The bar 50 is provided with holding notches 54 (Fig. 4) in its lower face and is normally depressed by a coil spring 55 (Fig. 6) mounted similarly to the spring 37 previously described.

A contact plate 60 (Fig. 4) is mounted in the casing 30 but is suitably insulated therefrom and is connected by a wire W (Fig. 13) to a battery B or other suitable source of current. A contact rod 63 (Fig. 4) is mounted in a block 64 slidable on a rod 65 fixed in the casing 30. A coil spring 66 holds the block 64 yieldingly in the position shown in Figs. 2 and 4. The block 64 is provided with a single tooth 67 adapted to engage the notches 46 and 54 previously described.

The re-setting stud 49 is provided with an arm 70 (Fig. 1) connected by a link 71 to a stud 72 in the shipper lever 22. When the shipper lever moves to the right in Fig. 1 on the stopping of the loom, the arm 70 will move clockwise, thus rock-

ing the shoulder 48 from the position shown in Fig. 4 to that shown in Fig. 2. Such movement causes the shoulder 48 to engage and depress the shoulder 47 of the actuating member 33 and the corresponding portion 74 (Fig. 5) of the holding bar 50.

When the loom is started, the shoulder 48 is returned to the position shown in Fig. 4, and the member 33 and bar 50 are released for downward movement by the springs 37 and 55. The bar 50 immediately swings downward to a position in which one of the notches 54 is engaged by the tooth 67 of the sliding block 64. The actuating member 33 would similarly move downward except for the fact that it is held in raised position by the support 42.

Upon indication of transfer by the weft detector 27, however, the forwardly extending end portion 75 (Fig. 14) of the detector 27 engages the forwardly extended portion of the support 42 and swings the same about its pivot 43 against the pressure of the spring 44, thus removing the support 42 from its supporting position under the actuating member 33, which member 33 then moves downward to the indicated position shown in Fig. 7, with its outermost notch 46 engaging the tooth 67.

A plate or bunter 80 (Fig. 1) is secured to the front of the lay 21 and moves forward in position to engage the rear end of the member 33 whenever the member 33 is in the lowered position indicated in Fig. 7. The plate 80, however, clears the member 33 when the member 33 is in the raised position indicated in Figs. 2 and 4.

The plate 80 engages the member 33 just before the lay reaches front center and moves the member 33 forward a distance substantially equal to the space between two successive notches on the member 33 or holding bar 50. Consequently, as the lay moves forward after indication, the plate 80 engages the member 33 and moves the sliding block 64 and contact bar 63 to the position indicated in Fig. 8.

The block 64 is held in this position by the holding bar 50, while the lay and plate 80 thereafter move rearward. The actuating member 33 also returns to its initial rearward position, in which position, however, the tooth 67 now engages the second notch in the member 33.

On the next forward movement of the lay, the sliding block 64 is moved to the position shown in Fig. 9, and on the third pick the block 64 is moved to the position shown in Fig. 10, in which the contact bar 63 engages the contact plate or member 60 and thus connects the wire W through the loom frame to the ground.

Any suitable loom-stopping mechanism may be included in the circuit of the battery B and it is convenient to use for this purpose the stopping mechanism of an electric warp stop motion, as indicated diagrammatically in Fig. 13. If the loom is not thus equipped, the battery B may be connected through a magnet M to the ground, said magnet effecting loom-stoppage through devices of any usual kind and forming no part of my present invention.

The operation of my invention is believed to be clearly apparent from the foregoing description but may be briefly summarized as follows:

During the normal operation of the loom with a sufficient supply of weft in the active shuttle, the detector 27 will be pushed directly forward as the lay approaches front center and the support 42 will hold the actuating member 33 in the raised position shown in Figs. 1 and 4. When

the weft supply in the shuttle S becomes substantially exhausted, the detector 27 will slip sidewise, removing the support 42 and allowing the actuating member 33 to swing downward to the position shown in Figs. 7 and 11 and into position for engagement by the plate 80 (Fig. 1).

Assuming that the shuttle S is in the plain or single box end of the lay when indicated by the detector 27, the actuating member 33 will receive its first forward movement by the plate 80 on the next pick, when the shuttle S is at the drop box end of the lay (Fig. 8). On the next forward beat of the lay, the member 33 will receive its second forward or counting movement from the plate 80, at which time the alternate shuttle will be at the plain end of the lay, assuming that the shuttles become alternately operative at two pick intervals (Fig. 9).

On the third pick after indication, both shuttles will be at the drop box end of the lay and the electrical stopping mechanism circuit will be closed at 60 (Fig. 10) as the lay reaches front center, with the shuttle box empty on the plain end of the lay.

The usual mechanism for stopping the loom through the action of the knock-off mechanism and brake requires about three-quarters of a revolution of the crank-shaft to stop the loom after the electrical circuit is closed. Consequently the original indicated shuttle S will be picked to the plain end of the lay, and the loom will be stopped approximately at bottom center, with the shed open and with the shuttle S conveniently positioned for replacement or replenishment.

By changing the number of teeth in the actuating member 33 and holding bar 50, the number of picks intervening between indication and loom stoppage may be increased or decreased as desired. It will be noted that my improved loom stopping mechanism operates entirely independent of the usual filling stop motion and protector mechanism, and that the lay is brought to rest through the action of the knock-off and brake mechanism as is usual upon an indication of warp breakage.

Having thus described my invention and the advantages thereof, I do not wish to be limited to the details herein disclosed, otherwise than as set forth in the claims, but what I claim is:

1. In a loom having one plain single-box end and having electrically controlled loom stopping mechanism, in combination, a weft detector mounted at said plain end, a circuit-closing device for said stopping mechanism, and means to actuate said device to close said circuit after a predetermined number of picks of the loom following indication of substantial weft exhaustion by said weft detector.

2. In a loom having one plain single-box end and having electrically controlled loom stopping mechanism, in combination, a weft detector mounted at said plain end, a circuit-closing device for said stopping mechanism, and means to move said circuit-closing device in a series of steps to circuit-closing position, each step corresponding to one pick of the loom following indication of substantial weft exhaustion by said weft detector.

3. In a loom having one plain single-box end and having electrically controlled loom stopping mechanism, in combination, a weft detector mounted at said plain end, a circuit-closing device for said stopping mechanism movable in a series of steps to circuit-closing position, and

means to move said device one step for each pick of the loom following indication of weft exhaustion until contact is completed and the loom is stopped.

- 5 4. In a loom having one plain single-box end and having loom stopping mechanism, in combination, a weft detector, and means releasable thereby and effective to cause said stopping mechanism to operate, said means including counting devices effective to delay the action of the loom-stopping mechanism for a predetermined number of picks following indication of substantial weft exhaustion, and said counting devices including a sliding member, an actuator therefor, a spring opposing sliding movement of said member, a holding bar positively preventing return movement of said sliding member, and automatic means to render said holding bar inoperative on loom stoppage.
- 10 5. In a loom having one plain single-box end and having loom stopping mechanism, in combination, a weft detector, and means releasable thereby and effective to cause said stopping mechanism to operate, said means including counting devices effective to delay the action of the loom-stopping mechanism for a predetermined number of picks following indication of substantial weft exhaustion and said counting devices comprising a movable control device, a feed bar effective to 15 advance said device step by step to operative position, said feed bar being normally maintained in stationary inoperative position, and means mounted on the lay and engaging and moving said feed bar at each forward beat of the lay after 20 indication of substantial weft exhaustion.
6. In a loom having one plain single-box end and having loom stopping mechanism, in combination, a weft detector, means releasable thereby and effective to cause said stopping mechanism to operate, said means including counting devices effective to delay such action of the loom-stopping mechanism for a predetermined number of picks following indication of substantial weft exhaustion, and said counting devices comprising a movable control device, a feed bar effective to 25 move said device step by step to operative position, said feed bar being normally maintained in stationary inoperative position, means mounted on the lay and engaging and moving said feed bar at each forward beat of the lay after indication of substantial weft exhaustion, and a holding bar cooperating with said feed bar and preventing return movement of said control device until after 30 loom-stoppage is effected.
7. In a loom having one plain single-box end and having loom stopping mechanism, in combination, a weft detector, means releasable thereby and effective to cause said stopping mechanism to operate, said means including counting devices effective to delay such action of the loom-stopping mechanism for a predetermined number of picks following indication of substantial weft exhaustion, and said counting devices comprising a movable control device, a feed bar effective to 35 move said device step by step to operative position, means to move said feed bar at each forward beat of the lay after indication of substantial weft exhaustion, a holding bar cooperating with said feed bar and preventing return movement of said control device until after loom-stoppage is effected, and automatic means to release 40 said feed bar and said holding bar as the loom is stopped.

8. In a loom, loom stopping mechanism, a weft detector, an operating element fixed on the lay, an actuating device released by said weft detector upon indication of substantial weft exhaustion and movable into the path of said operating element when thus released, and counting means effective to delay the operation of said loom-stopping mechanism for a predetermined number of picks after the release of said actuating device, said counting means comprising a sliding block having a single tooth, a feed bar having a plurality of notches and movable a limited distance endwise by said operating element as said element approaches front center, a holding bar having a plurality of holding notches for said sliding block, a spring yieldingly opposing forward movement of said block, and additional springs acting to press said feed and holding bars toward said block.

9. In a loom, loom stopping mechanism, a weft detector, an operating element fixed on the lay, an actuating device released by said weft detector upon indication of substantial weft exhaustion and movable into the path of said operating element when thus released, and counting means effective to delay the operation of said loom-stopping mechanism for a predetermined number of picks after the release of said actuating device, said counting means comprising a sliding block having a single tooth, a feed bar having a plurality of notches and movable a limited distance endwise by said operating element as said element approaches front center, a holding bar having a plurality of holding notches for said sliding block, a spring yieldingly opposing forward movement of said block, and additional springs acting to press said feed and holding bars toward said block.

10. In a loom having one plain single-box end and having loom-stopping mechanism, in combination, a weft detector, means effective to cause said loom-stopping mechanism to operate, a device to actuate said latter means step by step, said device being normally maintained in stationary inoperative position, an operating element fixed on the lay and normally clearing said actuating device but engaging and moving said actuating device on every forward movement of the lay after indication of weft exhaustion, and a member normally holding said actuating device out of the path of said operating element, said detector being directly operative to remove said member and to release said device upon indication of substantial weft exhaustion.

11. In a loom, loom stopping mechanism, a weft detector, an operating element fixed on the lay, an actuating device normally maintained in stationary inoperative position, said actuating device being released by said weft detector upon indication of substantial weft exhaustion and being movable into the path of said operating element when thus released, said operating element engaging and moving said actuating device on every forward movement of the lay after indication of substantial weft exhaustion, and counting means effective to delay the operation of said loom-stopping mechanism for a predetermined number of picks after the release of said actuating device.

OSCAR V. PAYNE.
